OSCILLATING VALVE

Filed Jan. 23, 1929

INVENTOR:—
JOSEPH GAMACHE.
By *Marion P. Smith* ATTY.

UNITED STATES PATENT OFFICE

JOSEPH GAMACHE, OF LOS ANGELES, CALIFORNIA, ASSIGNOR TO IMPERIAL OSCILLATING VALVE COMPANY, OF LAS VEGAS, NEVADA, A CORPORATION OF NEVADA

OSCILLATING VALVE

Application filed January 23, 1929. Serial No. 334,467.

My invention relates generally to valves and more particularly to an oscillating valve that is especially designed for controlling the inlet of gaseous fuel charges to the combustion chambers of internal combustion engines and likewise for controlling the discharge or exhaust of the burnt products of combustion from the combustion chambers.

The principal objects of my invention are to generally improve upon and simplify the construction of the existing forms of oscillating valves to provide simple and efficient means for converting the rotary motion of a cam shaft to oscillatory movement and imparting said movement to the valve, further to provide an oscillating valve and its actuating mechanism that is capable of being readily assembled or taken apart and to construct and mount the valve so that it operates with a minimum degree of friction.

Further objects of my invention are to provide an oscillating valve of the character referred to that is relatively simple in construction, inexpensive of manufacture, efficient and reliable in operation, and which acts to positively control, without leakage, the flow of gaseous fuel to the combustion chambers of an engine, and likewise to control the discharge of the burnt gases from the combustion chambers.

With the foregoing and other objects in view, my invention consists in certain novel features of construction and arrangement of parts that will hereinafter be more fully described and claimed and illustrated in the accompanying drawings, in which:

Fig. 1 is a vertical section taken lengthwise through the center of an internal combustion engine cylinder and showing my improved valve associated therewith.

Fig. 2 is a horizontal section taken on the line 2-2 of Fig. 1.

Fig. 3 is an elevational view of the cam that is utilized for imparting oscillatory movement to the valve stem with parts of the motion converting mechanism in section.

Fig. 4 is a plan view of the link motion utilized for converting the rotary motion of

a cam shaft into oscillatory motion and transmitting same to the valve carrying stem.

Referring by numerals to the accompanying drawings which illustrate a practical embodiment of my invention, 10 designates the cylinder of an internal combustion engine, 11 the removable cylinder head within which is formed an extension 12 of the combustion chamber within the cylinder 10, and arranged for operation within the cylinder 10 is a piston 13.

Formed integral with and projecting laterally from the head 11 is an extension 14 through which is formed a throat 15 that establishes communication between the intake or exhaust manifold 16 and the clearance chamber 12.

Formed in the extension 14 is a vertically disposed valve chamber 17 that tapers gradually toward its lower end and arranged for oscillatory movement within this chamber 17 is a tapered valve 18.

Secured on top of the extension 14 is a removable plate 19 that functions as a head for the valve chamber and leading to an opening that is formed in the center of said head is a lubricant supply pipe 20.

Formed integral with the top of the valve 18 is a short cylindrical plug 21 that projects into a corresponding aperture or recess 22 that is formed in the underside of head 19. There is sufficient clearance between the top of valve 18 and the cylindrical plug 21 and the head 19 to permit the valve 18 to expand lengthwise when heated.

When the valve 18 is fitted into the tapered chamber 17 the lower end of said valve is spaced above the bottom of said chamber, thereby providing sufficient clearance to enable the valve to move downwardly, thereby maintaining a tight joint between the valve and the extension 14, even though wear should occur between said valve and the wall surrounding the chamber 17.

Depending from the valve 18 is an axially disposed stem 23 that is connected by a universal coupling 24 to the upper end of a stem 25, and said last mentioned stem is mounted for rotation in a cylindrical block 26 that is

secured on an extension 27 of the lower portion of the cylinder block.

Arranged on valve stem 23 between the extension 15 and the coupling 25 is an expansive coil spring 23^a that normally exerts downward pressure on said coupling and the valve stem with which the same is associated.

Arranged between the cylindrical member 26 and the stem 25 are suitable antifriction bearings 28 and a cone 29 that engages the upper set of these bearings and is engaged by a nut 30 that is mounted on a threaded portion of stem 25.

Bearing against the nut 30 is a lock nut 31 and as a result of the construction just described the stem 25 may always be retained for proper operative position within the cylindrical member 26 and its antifriction bearings.

Arranged for operation in suitable bearings below the lower end of stem 25 is a cam shaft 32 that is driven preferably from the crank shaft on the engine, and mounted on said shaft 32 are disks 33, the same being spaced apart to form a channel 34, which latter is provided with an offset portion or lateral extension 35. The axis of the cam shaft 32 is intersected by the axis of the valve stem 25.

Pivotedly secured to the underside of the extension 27 and to one side of the axis of the valve stem by means of a pin or bolt 36, is one end of a horizontally disposed lever 37 that extends across and beyond the axis of the valve stem, and formed in the outer portion of this lever is a short longitudinally disposed slot 38.

Formed integral with or fixed to the lower end of the stem 25 and positioned directly above the lever 37 is a short horizontally disposed crank arm 39 and depending from the outer portion thereof is a pin 40 that occupies the slot 38.

Suitably journaled on the underside of the lever 37 between the pivot pin 36 and the slot 38, and in axial alinement with the valve stem 25 is a roller 41 that projects into the channel 34 between the cam disks 33.

The valve 18 is provided with a chamber 42, and formed through the wall surrounding this chamber is a relatively large port 43 that is constantly in communication with that end of the throat or passageway 15 that communicates with the manifold 16 and formed through the wall of the valve is a smaller port 44 that is adapted, as the valve is oscillated, to intermittently move into registration with that portion of the throat or passageway 15 that communicates with the clearance chamber 12.

In the operation of my improved valve cam shaft 32 is rotated from the crank shaft of the engine and the roller 41 traversing the slot or passageway between the cams 33 is moved a short distance laterally as it passes through the lateral extension 35 of said passageway, and as a result the lever 37 is swung

upon its axis which is the pin or bolt 36, and the free end of said lever swings through an arc designated by α , Fig. 4.

Inasmuch as the pin 40 engages in the slot 38 formed in the free end of lever 37, said pin will swing with the lever 37 and as a result crank arm 39 carried by the lower end of the valve stem 25 will swing through an arc α , Fig. 4, and consequently partial rotary movement will be transmitted to the valve carrying stem 25.

Thus by providing the lever 37 and the crank arm 39, and which lever and crank arm have different radii, a relatively short lateral movement of the roller 41 between the disks 33 will be effective in swinging the crank arm 39 a sufficient distance to rotate the valve carrying stem 25 so that the port 44 of the valve will be brought into registration with the corresponding end of the throat or passage 15.

When this registration is effected gaseous fuel is free to pass from the manifold through the valve into the combustion chamber of the engine with which the valve is associated, or the burnt products of combustion may discharge from the combustion chamber through a similar valve to the exhaust manifold.

It will be understood that there are two valves for each engine cylinder, one valve taking care of the inlet of gaseous fuel to the combustion chamber and the other valve permitting the exhaust of burnt products of combustion from the combustion chamber.

The valve stem operates with comparatively little friction, due to the provision of the ball bearings 28 at the ends of the cylindrical member 26 and the universal coupling 24 that connects the valve stems 23 and 25 compensates for any variation in the axial alinement between the two parts of the stem.

Further, the coupling 24 permits the valve 18 and its stem 23 to be readily disconnected without disturbing the actuating parts of the valve and the spring 23^a normally exerts downward pressure against the coupling 24 so as to constantly draw the valve 18 downward in its chamber and thereby producing a fluid pressure tight joint between the surface of said valve and the surface of the chamber in which it is arranged.

During operation the valve is lubricated by suitable oil that is delivered to the valve chamber through tube 20.

Thus it will be seen that I have provided an oscillating valve that is relatively simple in construction, inexpensive of manufacture, capable of being readily assembled or taken apart, and which valve is very effective in performing the functions for which it is intended.

It will be understood that minor changes in the size, form and construction of the various parts of my improved oscillating valve

may be made and substituted for those herein shown and described without departing from the spirit of my invention, the scope of which is set forth in the appended claims.

5 I claim as my invention:

1. In an oscillating valve, a valve carrying stem, a crank arm projecting from the lower end of said stem, a lever fulcrumed at one end and having a pin and slot connection with said crank arm, a roller journaled on said crank arm, a roller journaled on said lever between its fulcrum and the pin and slot connection with said crank arm, and a cam for engaging and actuating said roller.

10 2. In an oscillating valve, a valve carrying stem, a crank arm carried by said stem, a lever fulcrumed at one end and having a pin and slot connection with said crank arm, said lever and crank arm having different radii, a roller journaled on said lever in axial alinement with the valve carrying stem, and a cam for engaging said roller and imparting swinging movement to said lever.

15 3. The combination with an internal combustion engine, of an oscillatory valve associated with said engine, a stem carrying said valve, a crank arm carried by said stem, a lever pivotally supported at one end, the opposite end having a pin and slot connection with said crank arm, a roller projecting from the intermediate portion of said lever, a cam shaft mounted for operation so that its axis is intersected by the axis of the valve stem, and a cam carried by said shaft and engaging said roller.

20 4. The combination with an internal combustion engine, of an oscillatory valve associated with said engine, a stem depending from said valve, a crank arm projecting from said stem, a lever fulcrumed at one end and having at its opposite end a pin and slot connection with said crank arm, a roller carried by said lever, which roller is coaxial with said stem, a cam shaft journaled for rotation and arranged so that its axis is intersected by the axis of the valve stem, and a cam carried by said shaft and engaging said roller.

25 In testimony whereof I affix my signature.
JOSEPH GAMACHE.
